UNITED STATES PATENT OFFICE

2,256,992

CURTAIN

Jesse Stam, Newton Center, Mass., assignor to
 Fairclough & Gold, Inc., Boston, Mass., a corporation of Massachusetts

Application March 6, 1941, Serial No. 381,994

5 Claims. (Cl. 156—10)

This invention relates to a curtain or drapery and is concerned with a novel arrangement of curtain body and a two-piece, ruffled, marginal band in which two strips are secured to each other and to the body, the arrangement being such that, if desired, these strips can be differentiated from each other, as by making one white and the other colored, or by making one a different color, or by making them in two tones of the same color, although the strips need not be thus differentiated.

The invention will best be understood by reference to the following description when taken in connection with the accompanying drawing of one specific embodiment thereof, while its scope will be pointed out more particularly in the appended claims.

In the drawing:

Fig. 1 is an elevation of a curtain embodying the invention;

Fig. 2 is a sectional view on an enlarged scale on line 2—2 of Fig. 1;

Fig. 3 is an elevation of the two-piece, marginal band before attachment to the curtain body;

Fig. 4 is a sectional view on line 4—4 of Fig. 3; and

Fig. 5 is an elevation illustrating the marginal band ruffled and attached to the body.

Referring to the drawing and to the embodiment of the invention illustrated therein by way of example, and having reference at first to Fig. 1, there is shown a curtain comprising in a general way a web or body 6 and a two-piece, marginal band 8. In the present example, (see Figs. 3 and 4) the band comprises two strips 10 and 12 of appropriate textile material, one of which, herein the band 12 is folded as at 14 to form two plies 16 which in turn, are folded as at 18 and the raw edges 20 are turned inwardly between the plies 16. As herein shown, the strip 10 has an outer, picot edge 22 and an inner, raw edge 24 which is inserted between and embraced by the plies 16, and secured in place as by a row of stitching 26. By thus making the band 8 in two pieces 10 and 12, the attractiveness of the curtain can be enhanced by making the two pieces of contrasting appearance, as by making the piece 10 white, for example, and the piece 12 colored, for example.

The two-piece band, as thus constituted, is then ruffed as a unit (see Fig. 5) and is secured as by two rows of stitching 28 and 30 to the top, bottom and one or both vertical edges of the body 6 which is of appropriate textile material.

Subsequently, the body is folded as at 32 inwardly to form a ply 34 whose raw edge 36 is turned under and is stitched as at 38. This fold may be simply an ornamental finish, as in the case of the vertical edges of the curtain, or in the case of one or both horizontal edges, it may constitute a rod-receiving pocket as in my Patent No. 2,156,231, issued Apr. 25, 1939, in which there are pockets at top and bottom and the curtain is reversible.

Having thus described one embodiment of the invention, what I claim and desire by Letters Patent to secure is:

1. In a curtain, the combination of a body, and a marginal band applied to at least one margin of said body, said band comprising two strips initially joined together by stitching and ruffled as a unit which is secured to said body by other stitching which retains the ruffles.

2. In a curtain, the combination of a body, and a marginal band applied to at least one margin of said body, said band comprising two strips, one of which is folded and has its folded edge directed inwardly, said strips being initially joined together by stitching and ruffles as a unit which is secured to said body by other stitching retaining the ruffles.

3. In a curtain, the combination of a body, and a marginal band applied to at least one margin of said body, said band comprising two strips, one of which is folded to embrace the other, said strips being initially joined together by stitching and ruffled as a unit which is secured to said body by other stitching retaining the ruffles.

4. In a curtain, the combination of a web constituting the body of the curtain, a two-piece, ruffled, marginal band in which there are two strips which overlap each other and one overlaps said body portion, and stitching extending through both strips and through said body portion and attaching them together.

5. In a curtain, the combination of a web constituting the body of the curtain, a two-piece, ruffled, marginal band in which there are two strips which overlap each other and both overlap said body portion, stitching extending through both strips and through said body portion and attaching them together, said web having a margin which is turned inwardly and overlies said stitching, and stitching attaching said margin to the body of said web.

JESSE STAM.
